UNITED STATES PATENT OFFICE

2,598,888

LUGGAGE

Paul H. Capra, Philadelphia, Pa.

Application September 23, 1949, Serial No. 417,398

2 Claims. (Cl. 217—60)

1

The present invention has to do with luggage and is concerned primarily with that type of luggage that is commonly known as hand luggage and which is used to store various articles for traveling purposes.

In accordance with conventional and now fairly well standardized practice, a piece of hand luggage ordinarily comprises two complementary parts which cooperate when in a closed position to define the interior material receiving compartment of the luggage. These parts are hingedly connected together and a clasp is usually employed to maintain the parts in closed position.

In accordance with present day practice when the clasp is released, the user must open the top part to obtain access to the interior.

The present invention has in view as its foremost objective, the provision of a piece of hand luggage, of the type indicated, which includes means for automatically opening one part relative to the other coincident with release of the clasp means that holds them together.

More in detail, the invention has as an object, the provision in a piece of hand luggage, of spring means that is located in close proximity to the hinge connection between the parts and which spring means is effective to cause relative opening movement of the luggage parts when the clasp means is released.

In carrying out this idea a bracket member is secured to an inner side wall of one of the luggage parts. This bracket member carries a pivot pin on which is pivotally mounted a lever. One end of this lever is pivotally connected to a link that has its other end pivotally connected to the other luggage part. A spring and cylinder assembly is also carried by the bracket and the spring of this assembly is attached to the other end of said lever.

The spring is an expansion coil spring and when the luggage parts are brought into closed position, the link and lever affect the spring to place it under compression. When the clasp is released, the spring affects the lever to cause pivotal movement thereof which force is transmitted through the link to cause relative opening movement of the luggage parts.

Various other more detailed objects and advantages of the invention such as arise in connection with carrying out the above noted ideas in a practical embodiment will, in part become apparent, and in part be hereinafter stated as the description of the invention proceeds.

The invention therefore comprises a piece of hand luggage that consists of two complementary

parts that are hingedly connected together and having a clasp for holding the parts in closed position together with spring means for causing said parts to automatically assume an open position coincident with release of said clasp.

For a full and more complete understanding of the invention, reference may be had to the following description and accompanying drawing wherein:

Figure 1 is a vertical section through a piece of hand luggage designed in accordance with the precepts of this invention.

Figure 2 is a view taken on an enlarged scale, mostly in elevation but with parts broken away and shown in section illustrating the actuating mechanism; and

Figure 3 is a front end view mostly in elevation but with parts broken away and shown in section of the piece of hand luggage shown in Figure 1.

Referring now to the drawing wherein like reference characters denote corresponding parts, and first more particularly to Figures 1 and 3, there is therein illustrated a piece of hand luggage which may be taken as typical of one type which is now meeting with the approval of the using public. This piece of luggage comprises the complementary parts A and B. For the purposes of this specification, the part A will be called the top and the part B will be called the bottom or main body part. The top part A comprises a top wall 10, a front wall 11, a rear wall 12, and two oppositely disposed side walls 13.

At this point it is well to note that both of the luggage parts A and B may be made from any of the materials which are commonly used in the luggage art. The invention has particularly in mind the use of leather as a preferred material, although it contemplates the use of fabric compositions, plastics, and other materials from which hand luggage is made.

The bottom part B comprises a bottom wall 14, a front wall 15, a rear wall 16, and two oppositely disposed side walls 17.

The rear walls 12 and 16 have their edges in abutting relation as illustrated in Figure 1 and a hinge device represented at 18 serves to hingedly connect these rear walls 12 and 16 where they meet.

The front walls 11 and 15 also have edges in abutting relation and one or more clasp devices such as indicated at 19 may be employed for releasably holding the front walls with their edges in meeting relation. In this position, the parts A and B are in closed position. The clasps such as represented at 19 may include operat-

ing members indicated at 20 which may be availed of to release the clasps.

Referring now more particularly to Figure 2, a bracket member 21 which comprises a main plate 22 and a flange 23, that is normal thereto, is secured to one of the side walls 17 of the bottom part B. This anchorage may be effected in any preferred manner such as by using fastening means in the nature of rivets that are indicated at 24. Extending inwardly from the plate 22 of the bracket is a pivot pin 25 having a head 26. A lever which partakes of the characteristic of a bell crank is designated 27 and comprises two angularly disposed sections 28 and 29. A slot 30 is formed in this lever 27 at the angle between the sections 28 and 29 and this slot 30 receives the pin 25 with the head 26 maintaining the assembled relation. A link 31 is pivotally connected to the free end of the lever section 29 by a pin as indicated at 32. The other end of the link 31 is pivotally connected to one of the side walls 13 of the top part A as indicated at 33 in Figure 1.

The flange 23 is formed with an opening 34 in which is anchored one end of a cylinder 35. The cylinder 35 has a closed end as indicated at 36, while the other end is closed by a closure member 37 that is formed with a skirt 38 which is fitted into the mouth of the cylinder 35. The closure member 37 is formed with a central aperture 39 through which passes a pull rod 40. The outer free end of this pull rod 40 is turned over to form a hook or loop which is interlocked with an opening 41 formed in the lever section 28. The inner end of the pull rod 40 is located within the cylinder 35 and is secured to a spring follower 42.

An expansion coil spring 43 is positioned in the cylinder 35 about the pull rod 40 with one end engaging the spring follower 42 and the other end the skirt 38 of the closure 37.

Operation

While the operation of the mechanism above described is believed to be self-evident from the description of the parts given, it may be briefly outlined by noting that when the parts A and B are moved towards one another the lever 27 is affected by the link 31 to cause it to be rotated about the pin 25 in a clockwise direction. This means that the lever section 28 is moved away from the flange 23. This exerts a pull on the pull rod 40 that is transmitted to the spring follower 42, and as the latter is moved in the cylinder 35, the spring 43 is compressed.

Thus, when the parts A and B reach the closed position depicted in Figures 1 and 3, there is an appreciable amount of energy stored up in the spring 43. The clasp means 19 holds the parts A and B in closed position until such time as it is desired to open the piece of luggage.

Upon release of the clasp means the spring follower 42 is forced downwardly into the cylinder 35 by the spring 43 to exert a pull on the pull rod 40. This rotates the lever 27 in a counterclockwise direction. Thus, the lever section 29 is moved upwardly or outwardly of the luggage part B and due to the link 31 being pivotally connected to the free end of the lever section 29 and the luggage part A, the latter is moved upwardly into opened position.

An important feature of the present invention is the smoothness of the opening operation. This smoothness may be attributed, at least partially, to the cooperation of the spring follower 42

with the closed end of the cylinder 35. These parts function much in the manner of a dashpot. Thus, the opening is a smooth even motion rather than a quick snap or jerk.

While a preferred specific embodiment of the invention is hereinbefore set forth, it is to be clearly understood that the invention is not to be limited to the exact constructions, mechanisms, and devices illustrated and described because various modifications of these details may be provided in putting the invention into practice within the purview of the appended claims.

What is claimed is:

1. In a piece of hand luggage including complementary parts hingedly connected together and clasp means for holding said parts in closed position with one of said parts having a side wall, a bracket secured to said side wall, a pivot pin carried by said bracket, a lever having a slot receiving said pivot pin, a link having one end pivotally connected to one end of said lever and its other end pivotally connected to the other of said luggage parts, a cylinder carried by said bracket having a closed end and an open end, a closure for said open end, a spring follower for said cylinder between said closed end and said closure, a pull rod having one end connected to said spring follower with its other end connected to said lever at the side of said pivot remote from the connection of said link to said lever, said pull rod passing through an opening in said closure and an expansion coil spring in said cylinder about said pull rod and between said spring follower and said closure.
2. In a piece of hand luggage including complementary parts hingedly connected together and clasp means for holding said parts in closed position with one of said parts having a side wall, a bracket secured to said side wall, a pivot pin carried by said bracket, a lever consisting of angularly disposed sections having a slot at the angle between said sections receiving said pivot pin, a link having one end pivotally connected to one end of said lever and its other end pivotally connected to the other of said luggage parts, a flange on said bracket formed with an opening, a cylinder anchored in said opening having a closed end and an open end, a closure for said open end, a spring follower in said cylinder between said closed end and said closure, a pull rod having one end connected to said spring follower with its other end connected to said lever at the side of said pivot remote from the connection of said link to said lever, said pull rod passing through an opening in said closure and an expansion coil spring in its cylinder about said pull rod and between said spring follower and said closure.

60 PAUL H. CAPRA.
